Primary Examiner — Karen E Kearney*Assistant Examiner* — Sloan Rozin(74) *Attorney, Agent, or Firm* — Sughrue Mion, PLLC(57) **CLAIM**

The ornamental design for a desk, as shown and described.

DESCRIPTIONFIG. 1 is a perspective view from the top side of a desk.
FIG. 2 is a perspective view from the bottom side thereof.
FIG. 3 is a front elevation view thereof.

FIG. 4 is a right side elevation view thereof. A left side elevation view is a mirror image of the right side elevation view.

FIG. 5 is a top plan view thereof.

FIG. 6 is a rear elevation view thereof.

FIG. 7 is a bottom plan view thereof; and,

FIG. 8 is a perspective view from the top and rear side thereof, showing the desk in a manner of use.
The broken lines shown in the drawings illustrate portions of the desk that form no part of the claimed design.**1 Claim, 8 Drawing Sheets**(56)
